KNITTING MACHINE

Walter E. Ralston, Delavan, Wis., assignor to The
George W. Borg Corporation, Chicago, Ill., a
corporation of Delaware

Original application November 4, 1938, Serial No.
238,837. Divided and this application February
25, 1942, Serial No. 432,201.

3 Claims. (Cl. 66—71)

My invention relates to improvements in knitting machines.

The object of my invention is to provide a special draw cam mechanism whereby to simplify and speed up draw cam control operation thus making it possible to change the draw cam setting in the normal progress of a knitting machine operation and without stopping the machine for the adjustment of the draw cam.

In the drawings:

Figure 1 is a plan view of a knitting machine embodying my invention.

Figure 2 is an end view of a knitting machine equipped with my improved draw cam mechanism.

Figure 3 is a front view, from the operator's position, of my new draw cam adjusting device.

Figure 4 is a view of the underside of the cam block shown in Figure 3.

Figure 5 is a section on line 5—5 of Figure 3.

Like parts are designated by the same reference characters throughout the several views.

This is a division of my application Serial Number 238,837 filed November 4, 1938, now Patent No. 2,284,167.

The drawings show my invention embodied in a so-called hand knitting machine for the knitting of "flat" fabric and the product of such a knitting machine has heretofore been in the form of either a single weight simple flat web, or a double thickness flat web, or in the form of a single thickness web upon which the simplest forms of pattern have been made either by hand "decking" or by a laboriously operable cam control racking mechanism by means of which one entire needle plate, as for instance the front plate, has been laterally moved to the extent of not more than three or four needles. Obviously, my invention may be incorporated in other types of knitting machines whether hand or power operated as will be clearly seen from the following description.

In a hand knitting machine of the type shown in the drawings, a frame 10 is provided with two needle plates 12 and 13, the needle plate 12, as shown in my drawings, being the rear or back needle plate, and the needle plate 13 being the front needle plate since it is faced toward the operator's position when the device is operated as a hand knitting machine. In this description I shall refer to the needle plate 12 as the rear needle plate upon which a single thickness knitted fabric may be produced and upon which a pattern or the double thickness fabric may be

knitted by means of the needles in the front needle plate 13. It will be understood, of course, that the knitting operation is accomplished by the passage of yarn 14 through guide 15 into the hooks of the needles carried and guided by the needle plates 12 and 13, the guide 15 being reciprocated from end to end of the machine with cam blocks 16 and 17 which are carried and guided by cam block rails 18 and 19 in a manner well known

in this art. Heretofore the front plate 13 has been constructed with needle guides built into a solid plate extending clear across the machine from left to right, and, as indicated above, this entire 10 needle plate has heretofore been provided with means for "tracking" it laterally to the extent of one to three or possibly four needles. In any knitting machine calling for increased range of racking or in a machine wherein variation in the draw of the yarn is required to be oft repeated and especially in my new knitting machine described in my patent application Serial Number 238,837 wherein the plates are split and a diversification of plate movements and constant 20 variations in the draw of the yarn are common, my invention hereinafter described is of greatest use.

While the solid needle plate is mounted in a knitting position with the needle plate on the opposite side, it is possible to rack it from one end of the machine to the opposite end. Heretofore racking movement to the extent of three or four needles has been the limit in any given direction.

35 It will be obvious to any one skilled in this art that the successive racking would be virtually impossible with any of the types of yarn now used unless the drawing of each stitch by the draw cam in the cam blocks 17 is controlled and 40 adjusted as each type of work produced by the needles of the front plate is changed. For instance, the constant production of a rib stitch would require a given adjustment of the draw cam while the production of zig-zag stitching 45 would require a different setting of the draw cam. I have, therefore, provided a fingertip control for the adjustment of the draw cam in a draw cam control device shown most clearly in Figures 3, 4, and 5.

50 Each cam block is provided with two draw cams 70 and 71, and each of the draw cams is provided with a post 70' and 71'. These posts extend upwardly through the cam block and are in position to be contacted and controlled by a 55 pair of control levers 72 and 73. The pair of

control levers 72 and 73 is mounted upon a single fulcrum pin 74 and each of these control levers is a lever of the first class extending from a cam-like surface 75 which contacts the draw cam post to a latch lip 76, and one of the levers (73) in each pair is provided with a fingertip pad 77 comprising an extension of the lever.

Upon a separate latch post 78 I provide a pair of latch pin holders 79 and 80, each of which is provided with a latch pin 79' and 80', respectively. These latch pins extend through the latch pin holders 79 and 80 with which they are in threaded engagement, lock nuts being provided as shown. Latch pin holder 79 is provided with a spring 81 tending to withdraw latch pin 79' from engagement with the latch lip 76 of the lever 72 and a clip 82 secured to latch pin holder 80 overlies latch pin holder 79 to compel latch pin holder 80 to move upwardly with latch pin holder 79 but to permit the free downward movement of latch pin holder 79 without affecting latch pin holder 80.

With the draw cam adjusting devices, described above, it will be seen that the post of each draw cam may be adjusted along the slot in which it is mounted to move simply by the fingertip control of the operator for it is possible for the operator to move the draw cam upwardly for a tight draw merely by pressing downwardly upon the latch pin holders 79 and 80 thus causing latch pin 80' to engage the lip on lever 73, then as the knitting work progresses and a slight release of the draw cam is desired, pad 77 may be pressed by the fingertip of the operator whereby to release latch pin holder 79 and 80. The draw of the cam will then be reset by pressure upon holder 79, which in turn, as the work progresses, may be released by a second application of pressure upon pad 77.

Obviously the adjustment of the various positions of the draw cam may be accomplished by setting the adjustment of the latch pins 79' and 80'. Any basic adjustment of the levers 72 and 73 may be accomplished by means of a set screw 83 which positions the limit of "loosening" movement of the draw cam by determining the lowermost position of lever 72.

In the operation of my improved knitting machine in the creation of a pattern involving re-

peated changes in the racking of stitches produced by the front plate of the machine, the extreme usefulness of my quick draw cam adjustment will be apparent. The respective levers 72, 73 may be set at the predetermined adjustments required for particular types of stitching so that, under the control of their respective latches, the one or the other may be left in control of the draw cam as desired, thus making it only the work of a moment to shift from one type of stitching to the other as the work progresses. It has been found in practical commercial operation of my improved knitting machine that the operator soon becomes as proficient in the fingertip control of my draw cam as would a pianist in the fingering of the keys of a piano.

I claim:

1. An adjustable draw cam for a knitting machine and a frame therefor, said cam having a member positioned to engage control means for determining its position of adjustment, said control means comprising a plurality of levers fulcrumed on the frame and bearing against said member and a plurality of latches each releasably engageable with a lever whereby to hold the lever in a position of adjustment of the cam.
2. In a device of the character described, a knitting machine cam block, an adjustable draw cam movable from a position for loose stitch control to a position for tight stitch control, and a plurality of latch means alternatively engageable between the cam block and the draw cam for alternative positioning of the cam in any one of said plurality of positions of adjustment.
3. In a device of the character described, a knitting machine cam block, an adjustable draw cam movable from a position for loose stitch control to a position for tight stitch control, and a plurality of latch means alternatively engageable between the cam block and the draw cam for alternative positioning of the cam in any one of said plurality of positions of adjustment, said means including a pair of draw cam adjusting levers mounted upon said cam block and positioned to move the cam, and latches to releasably position said levers in selected positions of adjustment.

WALTER E. RALSTON.
